DESIGN FOR A HAIR CURLER

Harry Bonat, New York, N. Y., assignor to Samuel Bonat & Bro., New York, N. Y., a copartnership

Application October 19, 1945, Serial No. 123,006

Term of patent 14 years

(CL. D86—10)

To all whom it may concern:

Be it known that I, Harry Bonat, a citizen of the United States, and resident of the city of New York, county of New York, and State of New York, have invented a new, original, and ornamental Design for a Hair Curler, of which the following is a specification, reference being had to the accompanying drawing, forming a part thereof.

Fig. 1 is a perspective view a hair curler showing my new design.

Fig. 2 is a side elevational view thereof.

Fig. 3 is an end elevational view thereof on an enlarged scale.

I claim:

The ornamental design for a hair curler, substantially as shown.

HARRY BONAT.
